United States Patent Office

Des. 227,079
Patented June 5, 1973

227,079

BARREL OR THE LIKE

David Lustig, 168—03 67th Ave.,
Flushing, N.Y. 11365

Filed Aug. 31, 1971, Ser. No. 176,777

Term of patent 14 years

Int. Cl. D9—02

U.S. Cl. D9—170

FIG. 2

FIG. 1

FIG. 4

FIG. 3

FIG. 1 is a top plan view of a barrel or the like, showing my new design;

FIG. 2 is a side elevational view thereof;

FIG. 3 is a bottom plan view thereof;

FIG. 4 is a sectional view taken along line 4-4 of FIG. 1.

I claim:

The ornamental design for a barrel or the like, substantially as shown.
